UNITED STATES PATENT OFFICE.

GEORGE W. NORTON, OF FLUSHING, NEW YORK.

WINDOW-SCREEN.

1,076,693.

Specification of Letters Patent. Patented Oct. 28, 1913.

Application filed April 27, 1912. Serial No. 694,304.

To all whom it may concern:

Be it known that I, GEORGE W. NORTON, a citizen of the United States, and resident of Flushing, Long Island, in the county of 5 Queens and State of New York, have invented certain new and useful Improvements in Window-Screens, of which the following is a specification.

This invention relates to window screens 10 and particularly to flexible window screens such as are carried upon rolls and attached to the sash of the window so that when the sash is raised the screen is extended into the opening of the window.

15 An object of this invention is to provide improved means for actuating the roll carrying the screen, by the movement of the sash, so that when the sash is moved to close it, the extended screen will rewind upon the roll.

20 A further object of the invention is to provide a construction for actuating the roll which will insure that when the screen is greatly extended, that is, when the window is widest open, a considerable tension 25 will be placed upon the screen.

25 A further object of the invention is to provide a construction for actuating the roll, such that the higher the window is raised 30 the greater will be the tension placed upon the screen. This insures that the screen will not sag and insures also that the side edges will be held in place so that the screen will operate effectively to exclude insects.

35 The invention is set forth in the claims.

In the drawing which fully illustrates the preferred embodiment of my invention, Figure 1 is a front elevation showing the studding and frame of a window provided 40 with my screen and showing the window sash partly raised, with the screen attached, and so extending into and covering the window opening. Fig. 2 is a vertical section taken through the sill near the side of 45 the window frame with the sash and screen removed, and illustrating the preferred means for mounting and operating the screen. Fig. 3 is a vertical section taken on the line 3-3 through the window frame 50 at the window opening passing through the sill and showing the sash and the preferred manner in which the screen is carried on its roller and attached to the sash. Fig. 4 is a horizontal cross section through the side of 55 the casing, taken on the line 4-4.

Referring more particularly to the parts,

1 represents the side casement of a window frame having an inner sill or cap 2 and an outer sill 3.

In applying my invention, I may provide 60 a roller 4 which is supported under the outer sill 3 on suitable brackets 5, and this roller carries a fine mesh metal screen 6 which passes up through a longitudinal slot 7 in the member 3. At the slot 7 preferably a 65 metallic weather strip 8 is provided which projects upwardly and extends between the pulley stiles 9 of the casement, excluding rain from the slot. The pulley stiles 9 in the present embodiment are provided with 70 vertical slots 10 as indicated in Fig. 4, and the inner pair of these slots receive the edges of the extended screen 6. The rear edge of the stop bead 11 is preferably flush with the forward side of the slot 10 so as to form 75 virtually an extension of the forward wall of the slot. On the rear side of the slot I may provide a small guard bar 12 of angular form, as indicated in Fig. 4, the flange 13 of which is substantially flush with the 80 rear face of the slot.

The ends of the roller 4 are provided with sprocket wheels 14 which carry endless non-extensible chains 16, which pass up into the casement 1 in the aforesaid slots 85 10 in the stiles 9, and the stiles are provided at an elevated point with sprocket wheels 17 similar to the sprocket wheels 14 and about which the endless chains may pass. The free transverse edge of the 90 screen 6 is attached to a batten 18 which is preferably formed of a metal strip. The ends of this batten 18 are formed into reduced tips 20 which are attached to the forward runs of the chains 16. The batten 95 is provided with suitable hasps or catches 22 by means of which the screen may be readily attached positively or fixedly to, or detached from the bottom rail of the window sash 25. The lower sash 25 slides between the parting bead 26 and the stop bead 11, and has a slot 27 to receive the weather strip 8. The upper sash which is not illustrated may be provided with a screen of the same construction as that described and secured to the sash in the same manner.

100 When the sash 25 is raised it will be evident that the screen will be extended. The fact that the screen itself is formed of metal gives it a certain amount of resiliency 110 so that when a number of turns are on the roller 4 they act in a certain degree as a

spring tending to maintain the screen in tension. This insures that the screen will be held tight or taut when the window is opened a small amount.

5 The diameter of the roller 4 is preferably slightly less than the pitch diameter of the sprocket wheels 14. As the sash is raised, it extends the screen and at the same time the roller 4 is rotated positively by the 10 chain so as to pay out the screen to the moving sash. As the virtual diameter of the roller at this time is about the same as the diameter of the sprocket, the screen will be paid out sufficiently fast to follow up the 15 sash. As the sash is being raised the screen roll decreases in diameter and consequently the screen is paid out to the sash at a slower and slower rate. Since the roller body is of less diameter than the sprocket, 20 it follows that in the upper part of the opening movement of the sash the screen will not be paid out quite as fast as the sash moves. This will take up any slack that may exist in the screen and insures that 25 the screen will be kept taut. By my arrangement it will be seen that the peripheral movement of the roller 4 upon which the screen is wrapped, is slightly less than the corresponding movement of the sash; and 30 the roller surface has a constant amount of movement given to it for any given amount of movement of the sash at any point in the path of movement of the sash; and the amount of movement of the roller's surface 35 is preferably slightly reduced with respect to the movement of the sash.

While I have described above the pre-

ferred embodiment of my invention, it is understood that this is only one of the many forms my invention may take, and I do 40 not consider myself limited in the practice of my invention nor in my claims to the present embodiment of the invention.

What I claim and desire to secure by Letters Patent is:

1. A casement, a sash mounted to slide therein, a screen roller, a screen wrapped on said roller and attached to said sash, said roller being connected with said sash to move when said sash moves, said roller 50 being of a diameter such that the periphery of said roller has a reduced amount of movement with respect to said sash whereby said screen is maintained in tension when extended.

2. A casement, a window sash sliding therein, a screen attached to said sash so as to be drawn out into the window opening when said sash is raised, an endless sprocket chain attached to said sash, a sprocket wheel 60 guiding said chain, and a roller carrying a part of said screen rolled thereupon, said roller being of slightly less diameter than the pitch diameter of said sprocket wheel, whereby said roller may pay out said screen 65 at a slower rate than said sash moves and maintain said screen in tension.

Signed at New York in the county of New York and State of New York this 22nd day of April A. D. 1912.

GEORGE W. NORTON.
